Attorney.

UNITED STATES PATENT OFFICE

2,156,413

COWTAIL HOLDER

John Van Der Meulen, Blooming Grove, N. Y.

Application November 17, 1937, Serial No. 175,088

1 Claim. (Cl. 119—105)

This invention relates to improvements in cow tail holders.

The primary object of this invention is to provide a device of the above mentioned character which is adapted to hold a cow's tail during milking to prevent the cow's tail from swishing the milker.

A further object of this invention is to provide a device of the above mentioned character capable of grasping a cow's tail and holding the same attached to one of the cow's legs.

A still further object of this invention is to provide a device of the above mentioned character in which the gripping device as applied to the cow's leg is adapted to engage certain cords or nerves in the leg to prevent kicking, while the cow is being milked.

A still further object of this invention is to provide a device which is entirely sanitary due to the fact that it is unnecessary to grasp the cow's tail while applying the cow tail holder prior to the milking operation.

Other objects and advantages of the invention will become apparent during the course of the following description, taken with the drawing, wherein,

Figure 1 is a side elevational view of the device embodying this invention, illustrating the leg engaging rod;

Figure 2 is a top plan view illustrating the clamping devices for the leg and tail of the cow;

Figure 3 is an end elevational view showing the serrated clamping jaws for engaging the cow's tail;

Figure 4 is side elevational view showing the device as applied while milking.

In the drawing, wherein for the purpose of illustrating the invention and wherein like reference characters will be employed to designate like parts throughout the same, the reference character 5 will generally be employed to designate the cow's tail holder in general.

The invention comprises a piece of strap metal bent upon itself as at 6 to form arms 7 adapted to spring together at a central portion 8 as shown clearly in Figure 2. The arms 7 are looped as at 9 and are bent inwardly as at 10 to form a clamping portion 11. The complementary clamping portions 11 have their meeting edges serrated as at 13 more clearly shown in Figure 3 to securely grip the hairs of the cow's tail.

A pair of leg gripping arms 14 are formed on the clamping portions 11 and said arms 14 are arcuately curved and terminate in gripping jaws 15. The gripping jaws 15 comprise parallel rods which are adapted to engage the gambrel portion of a cow's leg as at L, shown in Figure 4. It will be noted that the cow's tail T also shown

in Figure 4 is shown passing through the loop formed by the curved arms or intermediate portion 9.

It is intended to form the clamp comprising the sections 7, 9 and 14 from resilient springy material which will normally assume the position shown in Figure 2 but which may be spread apart by means of a pair of handles 16 connected to the arms 7 by rivets or other fastening means as at 17. The free ends of the handles 16 are arcuately curved as at 18 to form finger gripping portions.

By applying pressure to the free ends of the arms 16 as at 18, the flexible strap clamp will separate on the return bent portion 6 as a fulcrum 15 and the jaws 15 will separate as well as the serrated jaws 13. In this position, the clamp may be applied to the cow's tail T so that the tail will pass through the loop formed by the curved arms 9 and the jaw bars 15 may be placed in position about the gambrel of the cow's leg L as shown in Figure 4. It will be noted that the milker will be able to apply the cow tail holder without touching the tail or the gambrel portion of the leg which is the usual custom in devices of this nature, and it has been found unsanitary due to the fact that the milker will milk the cow subsequent to the application of the clamp before washing his hands or otherwise sterilizing them.

It is also to be understood that the form of the invention herewith shown and described is to be taken as a preferred embodiment of the same and that various changes in the shape, size and arrangement of parts may be resorted to without departing from the spirit of the invention or the scope of the subjoined claim.

I claim:

In a cow-tail holder, a resilient sheet metal strip bent upon itself to provide a pair of side arms, the arms being directed towards each other for point contact, a pair of opposed outwardly arched portions in the arms with the arms having point contact between said arched portions to provide a closed loop intermediate the ends of the arms and an end loop open at its outer end, the point contact of the arms between the closed and open loops having the arm portions serrated to facilitate gripping the hair of a cow's tail, a right angularly extending rod at the outer end of each arm at the outer loop providing a pair of cow-leg gripping jaws and a handle carried by the outer side of each arm adjacent the fold line of the strip constituting operating handles for separating the points of contact of the normally closed resilient arms.

JOHN VAN DER MEULEN.
